3 SHEETS—SHEET 3.

UNITED STATES PATENT OFFICE.

JOHN SPENCER JUNKINS, OF SEWARD, PENNSYLVANIA.

PUNCHING, SHEARING, AND PRESSING MACHINE.

No. 907,812.

Specification of Letters Patent.

Patented Dec. 29, 1908.

Application filed April 2, 1908. Serial No. 424,756.

To all whom it may concern:

Be it known that I, JOHN SPENCER JUNKINS, a citizen of the United States of America, residing at Seward, in the county of Westmoreland and State of Pennsylvania, have invented certain new and useful Improvements in Punching, Shearing, and Pressing Machines, of which the following is a specification, reference being had therein to the accompanying drawing.

This invention relates to punching, shearing and pressing machines, and the primary object of my invention is to provide a novel machine that can be readily used for punching, shearing and pressing sheet metal, for the production of washers, cups and blanks preparatory for the production of certain articles.

A further object of this invention is to provide a novel machine having reciprocating heads for punching, shearing and pressing metal, said heads being arranged to coöperate or to operate independently, according to the work to be performed. In connection with one of said heads, a novel ejector or kick-off is employed for ejecting the product of the machine, while the same head is constructed to automatically eject the scrap or slugs.

With the above and other objects in view which will more readily appear as the invention is better understood, the same consists in the novel construction, combination and arrangement of parts to be presently described and then specifically pointed out in the appended claims.

In the drawings:—Figure 1 is a front elevation of my machine partly broken away and partly in section, Fig. 2 is a side elevation of the machine, Fig. 3 is a sectional view of a portion of the upper reciprocating head equipped with a shearing blade, Fig. 4 is a similar view of the same, illustrating a die for pressing a sheet metal, Fig. 5 is a front elevation of the lower portion of the machine, Fig. 6 is a similar view of the same partly broken away and partly in section, illustrating the ejector, Fig. 7 is a longitudinal sectional view of the same, Fig. 8 is an end view of the upper shaft and eccentrics carried thereby, Fig. 9 is a fragmentary view of the same in elevation, Fig. 10 is an end view of the lower shaft and the eccentric mounted thereon, Fig. 11 is a side elevation of a portion of the same, Figs. 12 to 15 inclusive are detail views of the eccentric straps, Fig. 16 is a

front elevation of a cage used in connection with the upper reciprocating head, Fig. 17 is a plan of the same, Fig. 18 is a front elevation of the lower reciprocating head, Fig. 19 is a side elevation of the same, Fig. 20 is a plan of a portion of the base of the machine, partly broken away, Fig. 21 is a side elevation of the same, and Fig. 22 is a front elevation of the ejector bearing.

To put my invention into practice, I provide a large structure or casting with a base or table 1 and an overhanging housing 2 providing a working space or throat 3 for the material to be operated upon by the machine.

In the top of the machine I journal a shaft 4, and at the bottom of the machine a shaft 5, these shafts 4 and 5 protruding from the rear end of the machine, also into the housing 2 and the base 1 respectively. Upon the shafts 4 and 5 are mounted gear wheels 6 and 7 respectively, these gear wheels meshing with a gear wheel 8 mounted upon a revolute shaft 9 having one end journaled in the rear end of my machine, while the opposite end thereof is adapted to be coupled to a suitable operating medium, as a motor or engine (not shown). The shafts 4 and 5 adjacent to the gear wheels 6 and 7 are provided with clutches 10 and 11 of a conventional form, these clutches being operated by bell crank levers 12 and 13 pivotally connected to the side of the machine and to a weighted bar 14, as at 15 and 16. The connection at 16 is made by a pin 17 loosely connected to the side of the machine, whereby the clutch 10 can be operated independently of the clutch 11, the object of which will presently appear. The lower end of the bar 14 is pivotally connected, as at 18, to a lever 19, fulcrumed as at 20, upon a stud post 21 carried by the side of the machine. By treading upon the forward end of the lever 19, the bar 14 can be elevated to throw the sockets 10 and 11 into a position to operate the shafts 4 and 5 in unison, these shafts being simultaneously thrown out of operation when the tread lever 19 is released. This is accomplished by the weighted bar 14.

The end of the shaft 4 protruding into the housing 2 is provided with eccentrics 22 and 23 for straps 24 and 25, said straps being pivotally connected as at 26, to a reciprocating head mounted in the housing 2, this head and the elements just described being retained within the housing by a front plate 28. Fig. 2 mounted upon said housing and

which is shown detached in Fig. 1 in order to more clearly illustrate the above described parts.

The reciprocating head comprises a block 5 27, a shell 28 surrounding said block, a cage 29 secured to said shell, and a guide plate 30 secured by bolts 31 and nuts 32 to said cage. The block 27 carries a face plate 27^a provided with a socket 33 for a threaded stem 10 34, to which is attached a punch 35 by a cup 36. The punch 35 extends through a guide sleeve 37, carried by the guide plate 30. Before the punch 35 can be removed, it is necessary that the sleeve 37, guide plate 30 and 15 cup 36 be removed.

To relieve the eccentric straps 24 and 25 from the entire weight of the reciprocating head, I use a counter balance or weight 38 which is adjustably mounted upon an arm 20 39 fulcrumed in a bearing 40 carried by the side of the housing 2. The arm 39 is pivotally connected, as at 41 to a pin 42 mounted in a stirrup 43, pivotally connected to the central eccentric strap 25. The pin 42 is retained within the stirrup 43 by a spring 44.

Reference will now be had to the base of the machine. Upon the shaft 5 is mounted an eccentric 45 and surrounding said eccentric is a block 46, said block being housed in 30 an opening 47 provided therefor in the lower reciprocating head 48. The eccentric 45 and the shaft 5 are partially released from the weight of the reciprocating head by a counter-balance or weight 49 adjustably mounted 35 upon an arm 50, fulcrumed as at 51 in the base of the machine and connected to said lower head by a link 52. The base of the machine is provided with openings 53 whereby easy access can be had to the weight 49. 40 The upper end of the reciprocating head 48 is provided with a plurality of vertical openings 54, these openings being arranged transversely of the head 48 and to communicate with angularly disposed discharge 45 openings 55, said discharge opening 55 communicating with openings 56 formed in opposite sides of the base of the machine.

The reciprocating head 48 adjacent to the outer ends of each discharge opening is recessed, as at 57 to receive plates 58 carrying discharge chutes 59, said plates being secured by screw bolts 60. The discharge chutes 59 extend into the openings 56 when the head 48 is in either a raised or lowered position.

55 The upper end of the reciprocating head 48 is provided with two inverted T shaped grooves 61 and adjustably connected to said head by bolts and nuts 62 is a table 63. Bolts 62 are adapted to slide in the groove 61 when the table is adjusted. The sides of the table 63 are provided with bearings 64 for an injector 65. Pivottally connected to the sides of the ejector as at 66 are levers 67, these levers being fastened to the base of the 60 machine, as at 68. The levers 67 are pro-

vided with turn-buckles 69 for adjusting the throw or kick-off of the ejector 65.

Upon the table 63 is arranged an inclined platform 70, said platform being inclined towards an opening 71 formed in the front 70 plate 72 of the base of the machine. Protruding upwardly through the inclined platform is a hollow standard 73 having a die 74 adapted to extend upwardly into a die plate 75 provided therefor in the top plate 75 76 secured to the base of the machine. The shafts 4 and 5 protrude from the front of the machine and are provided with apertured collars 77, whereby said shafts can be manually rotated when adjusting the various elements actuated by said shafts.

In Fig. 3 of the drawings, I have illustrated the top plate 76 provided with a conventional shearing blade 78, while the cage 29 of the upper reciprocating head is provided with a depending shearing blade 79. These shearing blades are used for cutting sheet metal and are made of any desired size.

In Fig. 4 of the drawings, I have illustrated attachments for my machine whereby various kinds of articles can be produced by cutting and pressing sheet metal into various shapes. The head 27 is provided with a shaping head 82 and the cage 29 is provided 90 with a shearing blade 83. The bottom head 48 is provided with a shaping die 84 and secured to the top plate 76 is a shearing blade 85. In the operation of these shaping dies, the shaft 4 can be revolved from left to 95 right thereby cutting the metal in shape before the pressing dies engage the same.

Operation: My machine is controlled in operation by the lever 19 and the clutches 10 and 11. Assuming that washers are to be 105 produced by my machine, a sheet of metal from which the washers are cut and punched is placed upon the die plate 75. When the lower reciprocating head is elevated, the die 74 assists in supporting the sheet of metal while the upper reciprocating head descends and causes the punch 35 to provide the sheet of metal with an opening. A slight further downward movement causes the guide sleeve to engage the sheet of metal, and then both 110 of said reciprocating heads move downwardly a short distance together, causing the edges of the die plate 75 to shear the sheet of metal and allow an annulet or washer to lay upon the die 74 between the upper end 115 of said die and the punch sleeve 37. Since this sleeve and the punch 35 is under the die plate 75, the upper reciprocating head now raises and the lower reciprocating head descends a short distance to provide clearance 120 between the upper end of the die 74 and the bottom of the top plate 76. The washer is now ready to be ejected from the machine through the opening 71 formed in the front plate 72. As the lower reciprocating head 125 130

descends, the ejector 65 is elevated from the horizontal position shown in Fig. 21 to the vertical position shown in Figs. 6 and 7. This is accomplished by the levers 67 being 5 pivotally connected to the stationary base of the machine and to the ejector 65. When the ejector passes over the die 74, the washer thereon is kicked off on to the inclined platform 70 and is immediately discharged 10 through the opening 71. The material or slug cut from the washer passes downwardly through the die 74, standard 73, into either of the openings 54 and 55 and eventually passes from the side of the machine. The 15 movements of the reciprocating heads are entirely governed by the eccentrics 22, 23, and 45, and the operation of the machine is fully controlled by the lever 19.

In shearing and stamping material, the 20 bell crank lever 13 is disconnected from the bar 14, as shown in Fig. 2, whereby the lower reciprocating head will remain stationary and permit of the upper reciprocating head being used for either shearing, punching or 25 pressing.

My invention is susceptible to such structural changes as are permissible by the appended claims.

Having now described my invention what 30 I claim as new, is:—

1. A machine of the type described, comprising a structure having a base and an overhanging housing, a shaft journaled in said base, a shaft journaled in said housing, gear 35 wheels for simultaneously operating said shafts, clutch members arranged upon said shafts for controlling the operation thereof, a tread lever for moving said clutch members, an upper reciprocating head arranged in 40 said housing and actuated by the shaft thereof, a weighted arm for counterbalancing said reciprocating head, a cage carried by said head, a punch arranged in said cage and protruding therefrom, a reciprocating head arranged 45 in said base and actuated by the shaft thereof, said head having discharge openings formed therein, said base having openings formed therein communicating with said discharge openings, a table arranged 50 upon said reciprocating head, an ejector pivotally supported thereby, levers connecting said ejector with the base of said machine, an inclined platform carried by said table, a hollow standard carried by said table and extending 55 through said platform, a die arranged in said hollow standard, a die plate supported by said base for receiving said die and the punch of the upper reciprocating head, and means arranged in the base of said 60 machine for counterbalancing said lower reciprocating head.

2. A machine of the type described, comprising a structure having a base and an overhanging housing, a shaft journaled in said base, a shaft journaled in said housing, gear

wheels for simultaneously operating said shafts, clutch members arranged upon said shafts for controlling the operation thereof, a tread lever for moving said clutch members, an upper reciprocating head arranged in said housing and actuated by the shaft thereof, a weighted arm for counterbalancing said reciprocating head, a cage carried by said head, a punch arranged in said cage and protruding therefrom, a reciprocating head arranged in 70 said base and actuated by the shaft thereof, said head having discharge openings formed therein, said base having openings formed therein communicating with said discharge openings, a table arranged upon said reciprocating head, an ejector pivotally supported thereby, levers connecting said ejector with the base of said machine, an inclined platform carried by said table, a hollow standard carried by said table and extending through 75 said platform, a die arranged in said hollow standard, a die plate supported by said base for receiving said die and the punch of the upper reciprocating head.

3. A machine of the type described, comprising a structure having a base and an overhanging housing, shafts journaled in said structure, gear wheels for simultaneously operating said shafts, clutch members for controlling the operation of said shafts, a tread lever for controlling the operation of said clutch members, reciprocating counterbalanced heads adapted to be operated by said shafts, one of said heads being located in said housing, and the other of said heads in 95 said base, the reciprocating head of said base having discharge openings formed therein, a platform carried by the head of said base, an ejector pivotally supported by said head and connecting with the base of said structure, an inclined platform supported by said table, a hollow standard extending upwardly through 100 said platform, a die carried thereby, and a die plate supported by said base and adapted to receive said die.

4. A machine of the type described, comprising a structure having a base and an overhanging housing, shafts journaled in said structure, an upper reciprocating head actuated by one of said shafts, a lower reciprocating head actuated by the other of said shafts, said lower reciprocating head having discharge openings formed therein, an ejector carried by said head and adapted to be actuated by a lowering movement of said head, a die carried by said head, a die plate arranged upon said base and adapted to receive said die, means carried by the first mentioned reciprocating head for operating on work mounted on said base, means carried by said 115 structure for counterbalancing said heads, and means arranged upon one side of said structure for controlling the operation of said shafts, substantially as described.

5. A machine of the type described, com-

prising a structure having a base and an overhanging housing, shafts journaled in said structure, an upper reciprocating head actuated by one of said shafts, a lower reciprocating head actuated by the other of said shafts, said lower reciprocating head having discharge openings formed therein, an ejector carried by said head and adapted to be actuated by a lowering movement of said head, a die carried by said head, a die plate arranged upon said base and adapted to receive said die, means carried by the first mentioned reciprocating head for operating on work supported on said base, and means carried by said structure for counterbalancing said heads.

6. A machine of the type described, comprising a structure having a base and an overhanging housing, shafts journaled in said structure, an upper reciprocating head actuated by one of said shafts, a lower reciprocating head actuated by the other of said shafts, said lower reciprocating head having discharge openings formed therein, an ejector carried by said head and adapted to be actuated by a lowering movement of said head, a die carried by said head, a die plate arranged upon said base and adapted to receive said die, means carried by the first mentioned reciprocating head for operating on work mounted on said base.

7. A machine of the type described, comprising a structure having a base and an overhanging housing, shafts journaled in said structure, reciprocating heads actuated by said shafts, a punch carried by one of said

heads, a die carried by the other of said heads, an ejector carried by said die-carrying head and actuated by a downward movement thereof, means for discharging the material operated upon by said punch and die, means for counterbalancing said heads, and means for controlling the operation of said shafts.

8. A machine of the type described, comprising a structure having a base and an overhanging housing, shafts journaled in said structure, reciprocating heads actuated by said shafts, a punch carried by one of said heads, a die carried by the other of said heads, an ejector carried by said die-carrying head and actuated by a downward movement thereof, means for discharging the material operated upon by said punch and die, and means for counterbalancing said heads.

9. A machine of the type described, comprising a structure having a base and an overhanging housing, shafts journaled in said structure, reciprocating heads actuated by said shafts, a punch carried by one of said heads, a die carried by the other of said heads, an ejector carried by said die-carrying head and actuated by a downward movement thereof, and means for discharging the material operated upon by said punch and die.

In testimony whereof I affix my signature in the presence of two witnesses.

JOHN SPENCER JUNKINS.
